UNITED STATES PATENT OFFICE

137,534

DESIGN FOR A BIRD FIGURE

James F. Buffenbarger, Middletown, Ohio, assignor to The Gardner-Richardson Company, Middletown, Ohio, a corporation of Ohio

Application June 25, 1943, Serial No. 110,523

Term of patent 14 years

(Cl. D29—23)

To all whom it may concern:

Be it known that I, James F. Buffenbarger, a citizen of the United States and a resident of Middletown, in the county of Butler and State of Ohio, have invented a new, original, and ornamental Design for a Bird Figure, of which the following is a specification, reference being had to the accompanying drawing, which forms a part thereof.

In the drawing:

I claim:

The ornamental design for a bird figure, substantially as shown.

JAMES F. BUFFENBARGER.
